Primary Examiner — Rhea Shields(74) *Attorney, Agent, or Firm* — Ladas & Parry LLP(57) **CLAIM**

The ornamental design for a packaging pot, as shown and described.

DESCRIPTION

FIG. 1 is a perspective view showing a packaging pot of my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a right-side elevational view thereof; and,

FIG. 7 is a left side elevational view thereof.

In FIG. 4, the broken lines are for the purpose of illustrating portions of the packaging pot that forms no part of the claimed design.
